CARPET.

No. 15,865.

Patented Feb. 24, 1885.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,865, dated February 24, 1885.

Application filed January 14, 1885. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 Various large flower and leaf figures, symmetrical and otherwise, are carried on a stem-work of short angular stems that traverse the entire face of the design. Some of these figures

have projecting cross-like portions, and one has a blossom-spray. The space between these 20 connected flower and leaf figures is filled in with small disconnected tendril-like ornamentation, constituting a ground, all as clearly shown in the photograph.

I claim—

1. The design for a carpet, consisting of the connected flower and leaf figures, substantially as shown and described.
2. The design for a carpet, consisting of the connected flower and leaf figures and the 30 ground, substantially as shown and described.

HENRY HUNT.
